OSCAR CHARLES ROESEN, OF BROOKLYN, NEW YORK, ASSIGNOR TO WOOD NEWS-PAPER MACHINERY CORPORATION, OF NEW YORK, N. Y., A CORPORATION OF VIRGINIA.

SMOOTHING DEVICE FOR IMPRESSION BLANKETS.

Application filed June 7, 1926, Serial No. 114,227. Renewed February 12, 1929.

This invention relates to means for working out or eliminating the depressions and projections that the blanket on the impression cylinder of a rotary printing press retains after a plurality of printing impressions.

The principal objects of the invention are to provide means by which the blanket is reduced more nearly to a uniform surface 10 after repeated impressions and to provide said means in a form in which it will continually smooth out the blanket as the press operates, thus making it impossible for any particular impression or repeated number 15 of impressions to cause the surface of the blanket to have deep depressions or high reliefs at any time.

Reference is to be had to the accompanying drawing in which the figure is a diagrammatic side view of the two couples of a perfecting web press showing a preferred form of this invention applied to each impression cylinder.

It is a well known fact that after an 25 edition of a newspaper has been completed the surfaces of the blankets around the impression cylinders are impressed with the design on their respective plate cylinders with which they came in contact during 30 printing. During the printing of the next edition the design on the plate cylinders may be of an entirely different nature. The points of greatest depression on the blanket are likely to be in different regions from the 35 points of greatest depression produced by the new plates. Poor printing is the result at the beginning of an edition and a number of imprints have to be thrown out. This gradually works out as the impressions are 40 repeated, but that is likely to be a long process.

This invention is designed to overcome these difficulties and eliminate the loss of a considerable amount of paper at the beginning 45 of each edition.

For this purpose I provide along each impression cylinder 10 an ironing device in the form of a roller 11. This roller extends across the entire width of the cylinder. It 50 is pressed by springs 12, located along a stationary part of the frame 13, against the surface of the impression cylinder. These

springs 12 are located at both ends of the ironing roller 11 or at intervals along the length thereof. Each roller 11 is mounted 55 on a pivoted frame 14 so that the springs will be readily effective for the purpose intended. The rollers are free on their studs or shafts and will rotate on their axes by the action of the impression cylinder itself. 60 Thus they will continually smooth out the impression which may be left on the blanket 15 on the impression cylinder.

In this way no impression can be made 65 very deeply and the surface of the blanket is kept practically uniform all the time. Therefore when the plates 16 on the plate cylinder 17 are changed they do not have to act against a blanket that has previously 70 been provided with deep depressions. They practically always work against what is equivalent to the surface of a new blanket except that this blanket may be compressed by the spring pressed rollers.

This eliminates the above mentioned difficulties and in fact makes the impression 75 better even on the first edition because the blankets do not become depressed at the points of heaviest printing as has been the case heretofore.

Although I have illustrated and described 80 only a single form of the invention I am aware of the fact that modifications can be made by any person skilled in the art without departing from the scope of the invention as expressed in the claims. Therefore I 85 do not wish to be limited to the details shown, but what I claim is:—

1. In a printing press, the combination 90 with an impression cylinder having a blanket, of movably mounted automatically adjusted means for continually ironing out the surface of the blanket as the press operates, for the purpose described.

2. In a printing press, the combination 95 with an impression cylinder and its blanket, of a roller extending throughout the length of the impression cylinder for rolling out the irregularities of the blanket; said roller being automatically adjusted to the irregularities in the blanket.

3. In a printing press, the combination 100 with an impression cylinder, of a roller extending parallel with the impression cyl-

inder and extending from end to end thereof and springs for pressing said roller against the cylinder to roll out irregularities all the way across the impression cylinder 5 blanket.

4. In a printing press, the combination with an impression cylinder, having a blanket thereon, of a freely rotatable roller arranged to be rotated by surface contact 10 with the impression cylinder and movably mounted to move freely toward and from it, and springs for constantly pressing said

roller against the blanket to iron out the blanket throughout the printing operation. 15

5. In a printing press, the combination with an impression cylinder having a blanket thereon, of movably mounted automatically adjusted means continuously in contact with the impression cylinder for reducing the irregularities in the surface of the 20 blanket between impressions.

In testimony whereof I have hereunto affixed my signature.

OSCAR CHARLES ROESEN.
